UNITED STATES PATENT OFFICE.

CHARLES V. STEWART, OF SANTA CRUZ, CALIFORNIA.

ADJUSTABLE WINDOW-SCREEN.

1,257,147.

Specification of Letters Patent. Patented Feb. 19, 1918.

Application filed August 14, 1917. Serial No. 188,154.

To all whom it may concern:

Be it known that I, CHARLES V. STEWART, a citizen of the United States, residing at Santa Cruz, in the county of Santa Cruz and 5 State of California, have invented new and useful Improvements in Adjustable Window-Screens, of which the following is a specification.

The present invention relates to improvements in the construction of window screens. The primary object of the invention is to simplify and improve the existing art by producing an adjustable window screen so constructed that the component parts thereof, reinforce one another; one wherein the lapping sections are brought into close contact with each other so that flies or small insects cannot enter therebetween, and also one in which the same will so engage in the 20 window casing and be so engaged by the sash and the casing lowered upon the said screen, as to effect a perfect joint therebetween which will also prevent the entrance of insects.

It is a further object of the invention to produce an adjustable window screen comprising similar parts each in the nature of a wooden frame, to secure to the frame metallic plates which lap the joints provided between the parts constituting the frames to reinforce the said frames and at the same time to receive the screening, two of the oppositely disposed plates on each of the frames being extended beyond the 35 edges of the said frames, the said extensions on one of the frames being bent upon themselves to provide guide ways for the extensions on the other frame, and wherein a single thickness of metal constituting what 40 may be termed a knife edge is arranged for free sliding in the said guide ways.

Other objects and advantages will appear as the nature of the invention is more fully understood, reference being had to the accompanying drawings, in which,

Figure 1 is a perspective view illustrating the arrangement of the screen in the window casing and engaged by a window sash.

Fig. 2 is a plan view of the screen removed from the sash.

Fig. 3 is a sectional view, approximately on the line 3—3 of Fig. 2.

Fig. 4 is a sectional view approximately on the line 4—4 of Fig. 2.

Fig. 5 is a sectional view approximately on the line 5—5 of Fig. 2.

Fig. 6 is a perspective view of one of the screen sections.

Fig. 7 is a similar view of the other screen section.

My improved screen, as illustrated in Fig. 1 of the drawings, is designed to be received in the window casing, the same being adjustable, may be brought to readily accommodate itself in the said casing, and the upper 60 edge of the said screen is engaged by the lower sash of the casing. As will herein-after appear, the engagement of the screen with the walls of the casing and its engagement by the window sash is such as to provide no space or gap between the contacting surfaces so that small insects can enter therebetween. It will also appear as the description progresses that the lap sections, comprising the screen so contact with each other 70 that no space is left therebetween for the entrance of insects.

Referring now to the drawings in detail, the screen sections are indicated by the numerals 10 and 11 respectively. Each of the 80 sections comprises a substantially rectangular wooden frame, the longitudinal members 12 whereof being of a greater width than the transverse or end members 13, and the longitudinal or side members 12 having their 85 ends engaged by the inner faces of the end members 13, suitable securing means, such as nails 14 being driven through the end members 13 and entering the side members 12. As the members 12 and 13 are cut in 90 equal lengths respectively, it will be apparent that the frames, for the sections 10 and 11, may be easily and quickly assembled. If desired, the contacting portions of the side and end members may be provided with 95 interengaging elements as for instance, tongues and grooves, but, as the screen or netting serves to reinforce the wooden frames and as the metallic plates, herein-after to be referred to, effectively compress 100 the frames at the connecting ends thereof, and still again, as it is one of the primary objects to produce a device which shall be simple, cheap and readily constructed, the nails 14 have been found amply sufficient in 105 the construction of the frames. The wire netting for each of the screens is indicated by the numerals 15—15, the same being laid over one of the faces of the said frames, and secured thereto by small brads 110 16 that pass through longitudinal or side plates 17—17 and transverse or end plates

18, the respective longitudinal plates being arranged over the longitudinal members 12 and the respective end plates being arranged over the respective end members 13 of the 5 wooden frames. The plates 17 extend the entire length of the frames so that the same bridge the points between the confronting surfaces of the side and end members of the said wooden frames, the securing brads 16 10 passing through the said plates 17 into both the side and end members 12 and 13 of the wooden frames materially reinforcing the said wooden frames as well as providing means for securing the netting 15 to the said 15 wooden frames. The longitudinal side plates 12 have their edges extending a suitable distance beyond the outer edges of the longitudinal members 12 of the wooden frames, but the end plates 18 are of a width 20 approximately equaling the width of the end members of the wooden frames. The extending edges of the plates 17 on the frame section 10 are bent upon themselves providing substantially U-shaped ways 19 which receive the projecting edges of the 25 plates 17 of the frame section 11, whereby to permit of the ready slideable adjustment of the said section 11 over the section 10. The protecting edges of the plates 17 of the 30 section 11 form tongues, which for distinction, are indicated by the numerals 20, the edges of the said tongues being designed to contact with the inner walls provided by the U-shaped grooves or ways 19 so that only a 35 small gap is left between the outer edges of the ways and the outer edges of the faces 20,

the said gap not being sufficient to permit of the passage therethrough of flies, mosquitos or such like insects. The end plates contacting with the inner faces of the side 40 plates permit of no gap being arranged between the confronting or lap portions of the sections, and from the foregoing description, when taken in connection with the accompanying drawings, the simplicity and 45 advantages of the construction will, it is thought, be apparent without further detailed description.

Having thus described my invention, what 50 I claim is:

The herein-described improvement in the construction of adjustable window screens, comprising two similar rectangular frames, 55 nails passing through the end members of each of the frames and entering the side members of the said frames, a wire netting on one of the faces of each of the frames, metallic plates arranged over the members comprising the frames and over the netting, and bridging the joint between the members 60 comprising the joints, brads passing through said plates and netting and entering the frame, the longitudinal plates of each of the frames projecting beyond the longitudinal members comprising the sides of the 65 frames, the projecting ends of the plates on one of the frames being bent over themselves providing substantially U-shaped ways, and said ways designed to receive the projecting plates on the other frame.

In testimony whereof I affix my signature.

CHARLES V. STEWART.
